UNITED STATES PATENT OFFICE.

EDWARD KENER, JR., OF BUFFALO, NEW YORK, ASSIGNOR TO BUFFALO CO-OPERATIVE STOVE CO., OF BUFFALO, NEW YORK, A CORPORATION OF NEW YORK.

FASTENING FOR STOVE-BASE MEMBERS.

Application filed March 27, 1924. Serial No. 702,186.

To all whom it may concern:

Be it known that I, EDWARD KENER, Jr., a citizen of the United States, residing at Buffalo, in the county of Erie and State 5 of New York, have invented new and useful Improvements in Fastenings for Stove-Base Members, of which the following is a specification.

This invention relates to an improved fastening between the several members of a base which is utilized for supporting the superstructure of stoves such as are now commonly employed in domestic kitchens.

Heretofore, the base members of a stove 15 have been usually connected by bolts extending through the several parts and similar means of fastening which were so constructed that some parts were exposed on the outer side of the base in the assembled position of the parts which is objectionable for the reason that this renders it impossible to first enamel the several parts of the base and subsequently fasten the same together without marring the enamel surface. Obviously any construction which does not permit of retaining the full finish of an enameled surface after the parts are completely assembled results in a marring of the beauty 25 of a stove and therefore renders the same less neat in appearance.

It is the object of this invention to provide a means of fastening the several members of a stove base which are so constructed that the main elements of the same are on 35 the interior of the base and therefore concealed from view, and which are so organized as to leave a practically smooth exterior or outer surface on the base members, which can be properly enameled before being assembled and which can be securely and reliably connected so as to produce a rigid base structure without liability of marring or scratching the outer enamel surface of the base and thus maintaining 45 the same in the most attractive condition.

In the accompanying drawings:

Figure 1 is a perspective view of the base of a stove equipped with my improved means of connecting the several members 50 thereof.

Figure 2 is a fragmentary side elevation of one corner of this base on an enlarged scale.

Figure 3 is a vertical section taken on line 3—3, Figure 2.

Figures 4 and 5 are detached views of two members of the base, the former being an inside view of one of the base bars and the latter an outside view of one of the legs.

Figure 6 is an inside view of one of the leg members of the stove base.

Figure 7 is a horizontal section taken on line 7—7, Figure 3.

Similar characters of reference indicate corresponding parts throughout the several views.

The stove base shown in the drawings as an example of one installation capable of advantageously employing my improved fastening comprises a plurality of horizontal bar members 10, preferably four in number, and a plurality of legs 11 also four in number, the several bar members and leg members being coupled with each other so as to form a substantially rectangular structure. Each of the legs is arranged at one corner of the base and has its upper end connected with two adjacent bar members which are arranged at right angles relatively to each other and fastened to the upper part of the respective leg by means of 70 my improved connection, which in its preferred form is constructed as follows:

At its upper end each of the legs is provided with two laterally projecting wings 12 which are arranged at right angles to each other in a horizontal plane. On the outer vertical side of each of these wings the same is provided with a recess or socket 13 which is elongated horizontally and opens at its outer end at the extremity of this wing while its inner end is of circular form. The bottom 14 of this recess is flat in the main portion thereof and the marginal edge 15 of this recess is inclined, this inclination being most pronounced at the 75 inner or curved portion of the recess.

On the outer side of the bottom of the recess the same is provided with a raised portion 16, the inner side 17 is constructed to form an inclined or beveled shoulder. On 80

the central part of the bottom 14 the same is provided with an opening 18 extending from the front to the rear side of the wing which opening is preferably elongated vertically in the form of a slot. Adjacent to opposite vertical edges of this opening each wing of the leg is provided on its rear side with two raised seats 19 and 20 which are provided midway of their height with 10 notches 21, 22, the bottoms of which are preferably rounded, as shown in Figures 3 and 6.

Each of the bar members 10 of the base is provided at its opposite ends with tenons 15 23, each of which projects horizontally from this bar about midway between the lower and upper edges thereof and is elongated horizontally. The form of each of these tenons is substantially the same as the dimensional lines of the recesses in the legs for which purposes the upper and lower edges of each tenon are arranged horizontally and the outer end thereof is of rounded or curved form so that each tenon will fit 20 a recess 13 in one of the legs. The marginal part of each tenon is beveled or inclined, as shown in 24, to conform to the beveled edge of the recess 13, the bevel portion on the rounded end of the tenon being more 25 pronounced to correspond to the more pronounced bevel portion of the inner rounded end of the recesses in the legs. Adjacent to its inner ends each of the tenons is provided on its inner side with a vertical rib 25, the 30 inner side 26 which faces away from the outer end of the extremity of the tenon being beveled.

About midway of its length each tenon is provided on its inner side with an inwardly projecting coupling lug 27 and this lug is provided with a horizontal opening 28. The numeral 29 represents a cotter or fastening pin which is adapted to pass through the opening 28 of the lug 29 and 45 engage with the notches of the seats 19 and 22 for the purpose of connecting the several parts.

In the assembled position of a leg member and bar member of the base, the beveled 50 edge of the tenon engages with the beveled edge of the recess on the leg member and the inclined shoulder 26 on the tenon engages with the shoulder 17 on the outer raised portion 16 of the leg so that upon 55 driving the cotter or fastening pin 29 through the coupling lug 27 and in engagement with the seats 19 and 20 the tenon of the bar member and the wing of the leg member will be firmly drawn against each 60 other and securely held against displacement laterally with reference to each other. While thus fastened together the shoulders 65 30, 31 arranged on the respective end of the bar member above and below its tenon engage with the shoulder 32, 33 on the re-

spective wing of the leg above and below the recess or socket thereof, so that the leg member and bar member are prevented from turning vertically relatively to each other, and instead are held reliably in their normal upright position. The several parts are so fitted that when the pin 29 is driven into place it will produce a wedging effect upon the raised seats 19 and 20 and thereby draw the coupling lug 27 inwardly and thus 75 securely fasten the bar member and leg member together without liability of any looseness developing in the parts after the same are assembled.

After these parts are thus connected the outer surfaces of each bar member and the respective leg member are flush and capable of being readily cleaned.

This stove base after its several parts are thus assembled presents no nuts, bolt heads, screws or similar fastenings on its outer side which enables these surfaces of the base members to be enameled or otherwise highly finished without liability of marring any of these surfaces during the operation of assembling and connecting the several base members. Due to this construction it is possible to not only assemble the members of a stove base much more rapidly and firmly inasmuch as no particular care is required to avoid marring the exterior and when the product is completed the same is left in an unmarred and in a neat appearing condition so far as its outer surfaces are concerned.

I claim as my invention:

1. A stove base comprising a bar member, a leg member, one of said members being provided with a recess and the other member having a tenon engaging with said recess, the bottom of said recess having an opening and said tenon having a lug extending through said opening, and a pin extending through said lug and engaging with that side of the member having the recess opposite to where the same is engaged by said tenon.

2. A stove base comprising a bar member, a leg member, one of said members being provided with a recess and the other member having a tenon engaging with said recess, the member having said recess being provided with an opening extending through the same from the bottom of the recess on the front side of this member to the rear side thereof, and the rear side of this last mentioned member having raised seats on opposite sides of said opening, and said tenon having a lug extending through said opening, and a pin passing through said lug and engaging said seats.

3. A stove base comprising a bar member, a leg member, one of said members being provided with a recess and the other member having a tenon engaging with said recess,

the member having said recess being provided with an opening extending through the same from the bottom of the recess on the front side of this member to the rear side thereof, and the rear side of this last mentioned member having raised seats on opposite sides of said opening, each seat having a notch, and said tenon having a perforated lug extending through said opening, and a pin passing through the perforated lug and engaging with the notches of said seats. 10

EDWARD KENER, JR.
